UNITED STATES PATENT OFFICE.

AUGUST J. DINKLAGE, OF EAST ORANGE, NEW JERSEY.

ANTICREEPING DEVICE FOR RAILS.

1.298.023.

Specification of Letters Patent. Patented Mar. 26, 1919.

Application filed December 26, 1916. Serial No. 138,790.

To all whom it may concern:

Be it known that I, AUGUST J. DINKLAGE, a citizen of the United States, and resident of East Orange, county of Essex, State of New Jersey, have invented a certain new and useful Improvement in Anti-creeping Devices for Rails, of which the following is a specification.

My invention relates to anti-creeping devices and more particularly to such devices as are used for preventing or arresting the creeping tendency of railroad rails. My improvement has for its object to increase the efficiency of such devices by so combining the cooperating parts thereof with the rail as to prevent unintentional displacement thereof for instance by the road ballast, ice and snow in winter or from any other cause. A further object of my invention is to simplify the construction and arrangement of the individual elements without affecting the efficiency of the device as a whole. Other objects will appear from the description hereinafter and the features of novelty will be pointed out in the appended claims.

Reference is to be had to the accompanying drawings, in which for the purposes of illustration and description I have shown several examples of my improvement and in which Figure 1 is a sectional view on the line 1—1 of Fig. 2 of one form of my improved device applied to a rail; Fig. 2 is a plan view thereof partly in section; Fig. 3 is a side elevation thereof; Fig. 3^a is an end view of the wedge included in this form; Fig. 4 is a view similar to Fig. 1 illustrating another form of my invention taken on the line 4—4 of Fig. 5; Fig. 5 is a plan view thereof partly in section; Fig. 6 is a side elevation thereof; Fig. 7 is a perspective view of the wedging element which forms part of this last mentioned arrangement; Fig. 8 is a view similar to Fig. 1 showing still another form of my improvement; Fig. 9 is a sectional view on the line 9—9 of Fig. 10 illustrating still another arrangement; Fig. 10 is a plan view thereof partly in section; Fig. 11 is a view similar to Fig. 9 showing still another form of my invention, and Fig. 12 is a section on the line 12—12 of Fig. 11.

In the example illustrated in Figs. 1, 2 and 3 the web of the rail is designated by the reference character 15 and the rail base as 16 the latter having its upper surfaces 16^a and 16^b at opposite sides of said web inclined in the usual way. The rail which in

the illustration represents a railroad rail further includes the usual head 17 and may be otherwise constructed in any usual manner and include any other features which may be common to rails of the type in question. My improved device as shown in the figures referred to, comprises a clamp 18 having a rail engaging jaw 19 which in practice extends around one edge of the base 16 and into contact with an upper inclined surface of said base, the illustration showing said jaw in contact with the surface 16^a. Preferably in rather close proximity to said jaw 19 the clamp is formed with a projection 20 which in active use engages the lower surface of said rail base 16 and together with the jaw 19 forms a space or recess 21 for the accommodation of a portion of the rail base as shown in Fig. 1. The clamp 18 is further constructed with a member 22 which terminates in a jaw 23, the member 22 inclining downwardly from the projection 20 relatively to the base 16 when the device is in use while the jaw 23 extends around the opposite edge of said base and over the surface 16^b thereof when the combination with the rail is as illustrated in Fig. 1. The clamp 18 is so constructed and proportioned that when it is in position on the rail the jaw 23 will be spaced from the inclined surface 16^b of the rail base and preferably so that that portion of said clamp which connects said jaw 23 with the member 22 is spaced from the edge of said rail base as shown in Fig. 1.

In the form being described a wedge 24 is located between the surface 16^b of the rail base 16 and the jaw 23 and is formed with an inclined surface 25 which in practice rests upon said surface 16^b in frictional engagement therewith as illustrated in Fig. 1, said wedge being forced up on said surface 16^b between the jaw 23 and the rail base 16 in a direction toward the web 15. This movement of the wedge will force the jaw 23 in a direction away from the surface 16^b so that the member 22 will act in the nature of a lever with the projection 20 as a fulcrum whereby the jaw 19 and the projection 20 itself are forced into closer gripping engagement with the surface 16^a and the lower surface of the rail respectively. In the preferred arrangement some means is provided for preventing the wedge 25 from being forced from beneath the jaw 23, the illustrated example showing this means as

- consisting of a pair of flanges 26 extending upwardly from the wedge 24 at opposite sides of said jaw 23, the latter, in other words being located between said flanges 26.
- 5 In practice the clamp 18 is located in close proximity to and preferably in actual contact with a tie 27, the arrangement being such that the clamp 18 will be held by said tie 27 against any appreciable movement in 10 the direction in which the rail tends to creep. The force exerted by said rail as it tends to creep from any cause will be communicated to the wedge 24 owing to the frictional engagement between the surface 25 of said 15 wedge 24 and the surface 16^a of the rail base 16. This force tends to carry the wedge 24 along with the rail in the direction of creep or in other words tends to force said wedge 24 from beneath the jaw 23.
- 20 As the separation of the wedge 24 and jaw 23 in this direction is prevented by the flanges 26 or their equivalents, said force, through the coöperation of the latter with the jaw 23 will be converted into a force whereby said 25 wedge 24 is caused to positively arrest the creeping tendency of said rail.
- The force above mentioned being exerted upon or near one end of the anti-creeping device will also tend to move it in a horizontal plane or to skew it relatively to the base 16 and will thus add to the gripping effect of said device upon the rail base. While the position of the clamp 18 with respect to the tie 27 will ordinarily prevent 30 any actual perceptible movement of the device in the manner last mentioned the effects of the force thus exerted will be present and will be added to the other forces to increase the grip of the device upon the rail base.
- 35 40 It will readily be seen that the rail will thus be firmly secured against any appreciable creeping and it will be evident that the greater the forces exerted by the creeping tendency of the rail the more firmly 45 will the rail base be gripped by the improved anti-creeping device and the greater will be the resistance interposed to the creep of the rail. At the same time it will be apparent that forces of lesser degree will similarly bring the parts of the device into 50 cooperation to overcome any creep in an efficient manner.
- 55 It will of course be understood that the parts are so proportioned and arranged that the movement of the wedge 24 toward the web 15 is never sufficient to completely disengage said wedge from the jaw 23 in this direction. In combining this form of my improvement with the rail the wedge 24 60 may first be placed upon the surface 16^a after which the jaw 23 of the clamp is placed over said surface and in loose connection with said wedge. The clamp is then moved toward the left in Fig. 1 relatively to the 65 wedge 24 and rail base 16 a sufficient dis-

tance to permit the jaw 19 to be raised and the recess 21 brought into registry with the edge of said rail base. The clamp is then individually moved back toward the right until the jaw 19 is in engagement with the 70 surface 16^a after which the wedge 24 may be driven up on the surface 16^b to an initial position in which the parts are firmly and securely clamped upon the rail base. It will 75 of course be understood that the combination of the anti-creeping device with the rail takes place at a suitable point to bring the clamp 18 into close proximity and preferably into actual engagement with a tie 27 as hereinbefore mentioned. It will further be apparent that the above is only an 80 example of how the device may be combined with the rail and that any other proceeding whereby the desired results are accomplished may be followed.

In the form shown in Figs. 4, 5, 6 and 7, the projection 20 is omitted in the clamp 18^a and the member 22^a thereof, is substantially straight throughout and in practice preferably lies in surface engagement with the 90 lower surface of the rail-base 16 as shown in Fig. 4. The clamp 18^a also includes a rail-engaging jaw 19^a similar to the jaw 19 and which likewise engages the surface 16^a of said base 16, said jaw forming a continuation of the 95 member 22^a and forming therewith a recess 21^a for the accommodation of the rail-base as in the previous form. At its opposite end the clamp 18^a when in use extends about the opposite edge of the rail-base 16 100 preferably in spaced relation thereto and terminates in a jaw 23^a which extends over the surface 16^b of said base at a distance therefrom in substantially the same way as does the jaw 23 of the form first described. 105 The lower surface of the jaw 23 is inclined downwardly to form a wedging surface 28 and is cut away for a distance inwardly from its free end to form a wedging surface 29 also inclined downwardly, both surfaces 110 28 and 29 being inclined relatively to the member 22^a and transversely to the major axis of said clamp as shown in Fig. 6. This construction further provides a shoulder 30 located at a distance from the end of the 115 jaw 23^a, which shoulder 30 is preferably inclined horizontally relatively to the web 15 as shown in Fig. 5. When operatively combined with the rail the clamp 18^a as in the form previously described is also in close 120 proximity to and preferably in actual engagement with a tie 27, the arrangement in this instance being also such that the clamp 18^a is held by said tie 27 against any material movement in the direction in which the rail 125 tends to creep. The wedge 24^a is provided with an inclined surface 25^a similar to the surface 25 and likewise resting upon the surface 16^b of the rail-base 16 in frictional engagement therewith as illustrated in Fig. 4. 130

In the form now being described the wedge 24^a is further provided with horizontal surfaces 31 and 32 located in different horizontal planes and inclined downwardly 5 toward the one end of the wedge as shown in Fig. 6, the surface 31 and 32 being joined by a vertical surface 33 which is inclined horizontally relatively to the major axis of the wedge as indicated in Fig. 5. 10 In practice the wedge 24^a is located between the jaw 23^a and the surface 16^b of the rail base 16 with the horizontal surfaces 31 and 32 beneath and in engagement respectively with the surfaces 28 and 29 of the 15 jaw 23^a as illustrated in Fig. 6 and with the vertical surface 33 in engagement with the shoulder 30 as shown in Fig. 5.

The wedge 24^a is also preferably so dimensioned as to engage the web 15 of the 20 rail as shown in Fig. 4 and is suitably shaped to make this arrangement possible.

In the preferred arrangement the surfaces 28 and 29 are inclined at angles which correspond substantially to the inclination of 25 the surfaces 31 and 32, while the angle of inclination of the shoulder 30 corresponds approximately to that of the surface 33. If desired the wedge 24^a may be provided, at 30 its large end with a head 34 or similar device adapted to receive the blows of a hammer or other implement which may be used to drive the wedge into its initial operative position, said head or the like in extreme cases also serving to prevent the wedge from 35 being completely forced from beneath the jaw 23^a.

In the operation of this form of my improvement the creeping tendency of the rail by reason of the frictional engagement 40 between the surfaces 16^b of the rail base and 25^a of the wedge 24^a will tend to carry the latter along in the direction of creep. This will bring about a movement of said wedge relatively to and transversely to the 45 jaw 23^a and through the coöperation of the jaw surfaces 28 and 29 with the wedge surfaces 31 and 32 will exert a lifting force on said jaw 23^a which is resisted through the coöperation of the clamp member 22^a and lower 50 surface of the rail base 16 as is clearly shown in Fig. 6. In consequence of this action the wedge 24^a will be more firmly jammed in between the jaw 23^a and the rail base, and the grip of the surface 25^a upon the surface 16^b increased, whereby a resistance to 55 the creeping tendency of the rail is set up, as will be clearly apparent. At the same time, owing to the fact that the wedge 24^a is in engagement with the web 15, the above 60 movement of the wedge will cause the vertical surface 33 thereof to exert a wedging action on the shoulder 30. In consequence of this coöperation of the surface 33 and shoulder 30, a force will be exerted upon 65 the clamp 18^a tending to move it toward the

right in Fig. 4 whereby the jaw 19^a will be forced upwardly on the surface 16^a and the rail base 15 forced farther into the recess 21^a. This operation causes the grip of the jaw 19^a upon said surface 16^a and that of the member 70 22^a upon the lower surface of the rail base 16 to be increased as will be readily apparent. In addition, owing to the fact that the forces due to the creeping tendency of the rail are exerted at or near one end of the clamp 75 18^a, a force tending to skew the latter relatively to said base will also be exerted in this form of my improvement. Even though this skewing tendency, owing to the fact that the clamp 18^a is in engagement 80 with a tie 27, may produce no perceptible actual movement of the clamp in the indicated manner relatively to the rail base, the effects thereof will be present and will assist in resisting the creeping of the rail. The 85 latter, in this form, is therefore also firmly and securely held against any material movement in the direction of its length. The arrangement shown in Figs. 4, 5, 6 and 7 may be operatively combined with the rail in the 90 same way as described with respect to the form shown in Figs. 1, 2 and 3, or in any other way whereby the results sought for may be accomplished.

In Fig. 8 I have illustrated a form of my 95 improvement which is substantially a combination of the two forms hereinbefore described. The jaw 23^b of the clamp 18^b which corresponds to the jaw 23 may be constructed in substantially the same way as is the 100 jaw 23^a excepting that the surfaces 28^a and 29^a thereof which correspond to the surfaces 28 and 29 need not be inclined unless this is desired. The jaw 23^b is also formed with a shoulder 30^b which is preferably inclined 105 horizontally in a manner corresponding substantially to the inclination of the shoulder 30. The wedge 24^b has surfaces 31^a and 32^a which correspond to the surfaces 31 and 32 and which may be similarly inclined or not 110 according to whether or not the surfaces 28^a and 29^a of the jaw 23^b are inclined or not, the surfaces 28^a and 29^a and 31^a and 32^a being always so constructed as to properly co-operate. The wedge 24^b is further formed 115 with a vertical surface 33^a connecting the surfaces 31^a and 32^a and corresponding to the surface 33 of the wedge 24^a, said surface 33^a being inclined horizontally to properly co-operate with the shoulder 30^a of the jaw 120 23^b, this part of the arrangement being substantially the same as in Figs. 4, 5, 6 and 7. In addition to this, said wedge 24^b is constructed with a surface 25^b corresponding to the surface 25 and arranged to fit and rest 125 upon the surface 16^b of the rail base 16. In the form shown in Fig. 8 the wedge 24^b is similar to the wedge 24 of Fig. 1 in that it does not contact with the web 15 of the rail as does the wedge 24^a in Fig. 4. 130

In the form now being described the parts occupy positions corresponding to those of the corresponding elements in Fig. 1, the wedge 24^b being located between the jaw 23^b and the rail base 16 with the surface 25^b of the wedge in frictional engagement with the surface 16^b of said rail base. As the wedge 24^b is carried along by the rail as the latter tends to creep, the coöperation of the wedge surface 33^a and the jaw shoulder 30^a will force the wedge 24^b or cause it to climb up on the surface 16^b of the rail base 16 toward the web 15 in the same way as is done in Fig. 1. As the wedge 24^b is moved in this manner it becomes firmly jammed between the jaw 23^b and the rail base 16 to an increased degree whereby the grip of the wedge surface 25^b upon the surface 16^b of the rail base will as a result be increased and a resistance to the creeping tendency set up as will be readily apparent. At the same time the described actuation of the wedge 24^b will exert a lifting force upon the jaw 23^b so that in this form also the member 22 will act in the nature of a lever with the projection 20 as a fulcrum. This will force the jaw 19 into closer gripping engagement with the surface 16^a of the rail base 16 and the projection 20 into closer gripping engagement with the lower surface of said rail base in the same way as in Fig. 1. If the surfaces 28^a and 29^a of the jaw 23^b and the surfaces 31^a and 32^a of the wedge 24^b are inclined to correspond to the surfaces 28, 29, 31 and 32 of Fig. 4 the action of the wedge upon the jaw in this respect will be the same as in the form shown in said figure and will provide an additional factor whereby the creeping tendency of the rail is resisted. Otherwise the operation of the form shown in Fig. 8 and its effects to resist the creeping tendency of the rail may be substantially the same as in the forms previously described. In the form now being described the parts are also so proportioned and arranged with respect to each other that the movement of the wedge 24^b toward the web 15 is never sufficient to completely disengage the wedge from the jaw 23^b in this direction. The parts comprising the present arrangement may be combined with the rail in the manner hereinbefore described or in any other way which may be found suitable or desirable.

In the form shown in Figs. 9 and 10 the arrangement includes a clamp 18^c which generally speaking is similar to the clamp 18^a and is combined with the rail base 16 in substantially the same way as shown in Fig. 4. The said clamp 18^c is formed at one end with a rail engaging jaw 19^b which forms a continuation of a member 22^b and forms therewith a recess 21^b for the accommodation of an edge portion of the rail base 16 in the same way as in Fig. 4, the member 22^b preferably lying in engagement with the lower surface of said rail base. At its other end the member 22^b is continued to form a jaw 23^c corresponding to the jaw 23^a and arranged in substantially the same manner with respect to the rail base as illustrated in Fig. 4. The jaw 23^c is cut inwardly from its free end as indicated at 35 and that portion thereof which lies below the cut is bent outwardly to form a member 30^b which extends transversely to the major axis of the clamp and corresponds in location and function to the shoulders 30 and 30^a hereinbefore referred to. In the form now being described the wedge 24^c is formed with a vertical wedging surface 33^b corresponding to the surfaces 33 and 33^a of the wedges 24^a and 24^b respectively, and is further constructed with a surface 25^c adapted to fit and rest upon the surface 16^b of the rail base 16 as in the forms previously described. In practice the wedge 24^c is located between the jaw 23^c and said rail base with the surfaces 25^c and 16^b in frictional contact and the wedge surface 33^b in engagement with the member 30^b, said wedge 24^c being further arranged and constructed so as to extend beneath said member 30^b as shown in Figs. 9 and 10.

When operatively combined with the elements comprising the form of my invention shown in Figs. 9 and 10 said elements occupy substantially the same positions as the corresponding parts shown in Fig. 4 excepting that in the illustrated example the wedge 24^c does not engage the rail web 15. As the wedge 24^c is carried along by the rail in its tendency to creep the coöperation of the wedge surface 33^b with the jaw member 30^b which in addition to its other functions acts as a guide for the wedge, will force the wedge 24^c up on the surface 16^b of the rail base 16 and toward the web 15. This action of the wedge in the first place produces a pressure upon the member 30^b whereby the clamp 18^c is forced toward the right in Fig. 9 with the result that the jaw 19^b is forced up on the surface 16^a and the rail base 16 is forced farther into the recess 21^b thus increasing the grip of the jaw 19^b upon the surface 16^a and of the member 22^b upon the lower surface of the rail base 16 so that a resistance to the creeping tendency of the rail immediately takes place. At the same time the surface 25^c of the wedge 24^c will be caused to increase its grip upon the surface 16^b of the rail base so that an additional resistance for overcoming the creeping tendency of the rail is exerted through the coöperation of the surfaces 25^c and 16^b. Owing to its construction the clamp 18^c may be readily stamped from suitable material if this should be desired thus reducing the cost of production and making it possible to produce the clamp in a minimum of time

whereby the output in a given time is increased as will be readily apparent. The form shown in Figs. 9 and 10 may be combined with the rail in the manner previously described or in any other suitable way and possesses all of the advantages and operates with the same efficiency as the forms previously described.

In the form illustrated in Figs. 11 and 12 the device includes a clamp 18^a which in the example shown is substantially the same as the clamps 18 and 18^b hereinbefore referred to and shown respectively in Figs. 1 and 8, but in which the jaw 23^a which corresponds to the jaws 23 and 23^b has its lower surface tapering downwardly or formed with inclines 36 and 37 which converge downwardly and meet at a point preferably on the vertical center line of the jaw. The upper surface of the wedge 24^a in the present form is constructed with inwardly inclined surfaces 38 and 39 converging for instance toward the longitudinal center line of said wedge the inclination of the surfaces 38 and 39 corresponding substantially to that of the jaw surfaces 36 and 37 as shown in Fig. 12.

In practice the clamp 18^a occupies a position on the rail corresponding to that occupied by the clamp 18, the wedge 24^a being located between the jaw 23^a and the rail base and in frictional engagement with the surface 16^b thereof and with the jaw surfaces 36 and 37 in operative engagement with the wedge surfaces 38 and 39 as shown in Fig. 12. As the wedge 24^a is carried along by the rail as the latter tends to creep for instance in the direction of the arrow in Fig. 12 the coöperation of the surfaces 36 and 38 will cause the jaw 23^a to climb up as it were on the wedge surface 38 whereby the member 22, projection 20 and jaw 19 will be actuated to clamp the rail against any creeping tendency which may occur. At the same time the coöperation of the surfaces 36 and 38 will interpose a resistance to the movement of the wedge 24^a in the direction of creep in much the same manner as do the flanges 26 of Fig. 1 or in other words prevents the wedge from being forced from beneath the jaw 23^a.

The arrangement now being described may be combined with the rail in the manner hereinbefore described or in any other way suitable to obtain the desired results and also possesses all of the advantages and operates with the same efficiency as any and all of the forms previously described.

It will be seen in all of the forms of my improvement herein illustrated and described that the creeping tendency of the rail produces forces which are exerted on the rail at both sides of the rail web to efficiently and quickly resist and overcome any creeping movement of the rail. The location of the active elements of my improve-

ment is always above the rail base out of contact with the road ballast so that the device is protected from interference by said ballast and against the possibility of some of said ballast becoming wedged between 70 the wedge and clamp and preventing the operation of the device in the intended manner. My improvement in all of its forms is extremely simple in construction and easy to assemble and combine with the rail thus 75 reducing the cost of production to a minimum and avoiding the necessity for skilled labor in applying and maintaining the device in operative condition whereby the cost of installation and maintenance is also reduced to a minimum point without in any way affecting the efficiency of the device as an anti-creep. As shown in several of the illustrated forms my improvement may be constructed and arranged in such a manner 80 that the horizontal surfaces of the clamp jaw and of the wedge which engage each other are flat. With such arrangement the danger of dislocation of the wedge in a reverse direction is reduced to a minimum. 90

In all of the forms the wedge may be driven to an initial operative position by means of a hammer or other suitable implement it being understood that the devices may occupy positions on the rail and relatively to the tie reversed from the positions shown this depending upon the direction in which the rail has a tendency to creep.

Various changes in the specific forms shown and described may be made within 100 the scope of the claims without departing from the spirit of my invention.

I claim:—

1. An anti-creeping device comprising a clamp having a rail engaging jaw at one end 105 and a second jaw at the other end spaced from said rail, a projection on said clamp adapted to engage said rail and means extending between said second jaw and said rail for rocking said clamp on said projection as a fulcrum whereby said rail engaging jaw and said projection are caused to grip said rail.

2. An anti-creeping device comprising a clamp having a rail engaging jaw at one end 115 and a second jaw at the other end arranged to extend over and at a distance from the upper surface of the rail base, a projection on said clamp adapted to engage the lower face of said rail base and a wedge between 120 said second jaw and the upper surface of said rail base for moving said clamp on said projection as a fulcrum whereby said rail engaging jaw and said projection are caused to grip said rail base.

3. An anti-creeping device comprising a tie-engaging clamp adapted to be operatively combined with a rail, and a wedge between 125 said clamp and said rail arranged to be influenced by the creeping force of said 130

- rail in a direction transverse to said clamp, said wedge being located entirely upon the upper surface of the rail base.
4. An anti-creeping device comprising a tie-engaging clamp having a jaw extending over and at a distance from the upper surface of the rail base, and a wedge located in its entirety upon said upper surface and extending between said jaw and said
- 5 surface of the rail base, said wedge coöperating with said surface to cause said clamp to grip the rail.
- 10 5. An anti-creeping device comprising a tie-engaging clamp having a jaw extending over and at a distance from the upper surface of the rail base, and a wedge located between said jaw and said surface of the rail base and arranged to be forced up on said surface in a direction toward the rail web whereby said clamp is caused to grip said rail.
- 15 6. An anti-creeping device comprising a tie-engaging clamp having a rail-engaging jaw at one end and a second jaw at the other end extending over and at a distance above the rail base, a wedge located in its entirety upon the upper surface of said rail base between said second jaw and said rail base, and a plurality of wedging surfaces on said
- 20 wedge located in planes extending transversely to each other and adapted to coöperate with said second jaw to cause said clamp to grip said rail.
- 25 7. An anti-creeping device comprising a tie-engaging clamp having a rail-engaging jaw at one end and a second jaw at the other end extending over and at a distance above
- 20 the rail base, a vertical shoulder on said second jaw at a distance from its free end, a wedge located in its entirety upon the upper surface of said rail base and extending between said second jaw and said rail base and a vertical wedging surface on said wedge coöperating with said shoulder to cause said clamp to grip said rail.
- 45 8. An anti-creeping device comprising a clamp having a rail-engaging jaw at one end and a second jaw at the other end extending over and at a distance from the rail base, a projection on said clamp engaging the lower surface of said rail base, a shoulder on said second jaw at a distance from its free end, a wedge located between said second jaw and said rail base and a vertical wedging surface on said wedge coöperating with said shoulder to force said wedge inwardly upon said base whereby said rail-engaging jaw and said projection are forced into gripping engagement with said rail base.
- 50 9. An anti-creeping device comprising a clamp having a rail-engaging jaw and a second jaw extending over and at a distance from the rail base, a member comprising an integral portion of said second jaw bent outwardly at an angle thereto, a wedge located between said second jaw and said rail base and a wedging surface on said wedge coöperating with said member to cause said clamp to grip said rail.
- 55 70 In testimony whereof I have hereunto set my hand.

AUGUST J. DINKLAGE.
